CLAIM

The ornamental design for a card reader, as shown.

DESCRIPTION

FIG. 1 is a front plan view of the reader portion and base portion of the new design;

FIG. 2 is a rear plan view of the reader portion and base portion of the new design;

FIG. 3 is a top plan view of the reader portion and base portion of the new design;

FIG. 4 is a bottom plan view of the reader portion and base portion of the new design;

FIG. 5 is a left side plan view of the reader portion and base portion of the new design;

FIG. 6 is a right side plan view of the reader portion and base portion of the new design;

FIG. 7 is a front plan view of the base portion of the new design;

FIG. 8 is a rear plan view of the base portion of the new design;

FIG. 9 is a top plan view of the base portion of the new design;

FIG. 10 is a bottom plan view of the base portion of the new design;

FIG. 11 is a left side plan view of the base portion of the new design;

FIG. 12 is a right side plan view of the base portion of the new design;

FIG. 13 is a front plan view of the reader portion of the new design;

FIG. 14 is a rear plan view of the reader portion of the new design;

FIG. 15 is a top plan view of the reader portion of the new design;

FIG. 16 is a bottom plan view of the reader portion of the new design;

(Continued)

FIG. 17 is a left side plan view of the reader portion of the new design; and,

FIG. 18 is a right side plan view of the reader portion of the new design.

The broken lines in FIGS. 1-18 are for environmental purposes only and form no part of the claimed design.

1 Claim, 15 Drawing Sheets
